UNITED STATES PATENT OFFICE.

OVERTON WINSTON, OF MINNEAPOLIS, MINNESOTA.

HEADLIGHT.

1,279,204.

Specification of Letters Patent. Patented Sept. 17, 1918.

Application filed May 31, 1916. Serial No. 100,825. Renewed February 16, 1918. Serial No. 217,714.

To all whom it may concern:

Be it known that I, OVERTON WINSTON, a citizen of the United States, residing at Minneapolis, in the county of Hennepin and State of Minnesota, have invented certain new and useful Improvements in Headlights; and I do hereby declare the following to be a full, clear, and exact description of the invention, such as will enable others skilled in the art to which it appertains to make and use the same.

My present invention relates to headlights for automobiles or other vehicles, and is in the nature of or an improvement on or modification of certain of the contact devices disclosed in my prior application S. N. 91,226, filed of date, April 14, 1916, and entitled "Headlight."

More particularly, the invention relates to the improved arrangement of the contact device in the socket and on the shank of a two-filament electric light bulb.

In the accompanying drawings which illustrate the invention, like characters indicate like parts throughout the several views.

Referring to the drawings:

Figure 1 is a vertical section with some parts broken away, showing the reflector, the lamp socket and light bulb;

Fig. 2 is a rear elevation of the shank of the light bulb; and

Fig. 3 is a fragmentary section of the front or contact end of one of the contact springs of the socket.

The light bulb 1 has two filaments 2 and 2^a, the outer ends of which are connected, respectively, to electrodes 3 and 4, and the inner ends of which are connected to an intermediate electrode 5, which electrodes are insulated from each other and supported by the shank of the light bulb. The shank of the light bulb has an axial contact 6 and two diametrically opposite segmental contacts 7 located in the rear end of its shank with the said contact 7 concentrically located around the said axial contact 6. These two contacts 7 are electrically connected, as shown, by a wire 7^a, and are, of course, insulated from the axial contact 6. The shank of the light bulb is surrounded by a metallic sleeve 8 that constitutes the outer contact of the light bulb and is electrically connected to the lower electrode 3. The electrode 5 is electrically connected to the axial contact 6, and the electrode 4 is electrically connect-

ed to the segmental contact 7, as shown, through the wire 7^a (see Fig. 1).

The filament 2 has its hot spot at the axis of the light bulb and the filament 2^a has its hot spot offset from said axis.

In the construction shown, the reflector 9 is surrounded by a flanged internally-threaded annular anchoring plate 10. The metallic contact sleeve 8 of the light bulb is shown as provided with radially projecting lugs 11 adapted to be inserted through internal longitudinal grooves of the lamp holding collar 13, and to be engaged with a serrated internal shoulder of the said collar, all as more fully illustrated in my said prior application above identified. The collar 13 is shown as provided at its inner end with an eccentric externally threaded portion 13^a that is screwed into the internally threaded portion of a socket tube 14, which, in turn, has screw-threaded engagement with the annular anchoring plate 10 and is thereby rigidly, but detachably held in working position. The holding collar 13 and socket tube 14 afford a bulb holding socket, by means of which the light bulb may be given adjustments both longitudinally and transversely of the axis of the reflector. The holding collar 13 is provided with a centering ring 15 of insulating material.

In the outer end of the socket tube 14 is an insulating block 16 and supported by and projected axially therefrom is a forwardly spring pressed contact plunger 17, the head 90 of which is normally spring pressed into contact with the axial contact 6 of the light bulb. The numeral 18 indicates a coiled contact spring which reacts against the insulating block 16 and is extended 95 through a centering ring 15 and normally engages always with at least one of the circumferentially spaced contacts 7. Here it is important to note that the front end of the said contact spring (see Fig. 3), is provided with a curved contact-engaging portion, substantially of the extent shown in Fig. 3, that is, in a plane at a right angle to the axis of the said spring, so that any point thereof, is adapted to engage with one 100 or the other of the said contacts 7. This non-spiral portion of the spring, in circumferential extent, is greater than the circumferential distance between the two contacts 7, so that it must always engage with at least 110 one thereof. This insures contact between the spring 18 and one or the other of the said

contacts in all adjustments of the light bulb, obviates the necessity of a complete annular contact on the end of the shank of the light bulb, and furthermore, affords a good bearing for the said spring in which the force of the spring is not exerted on a single point or small area. In fact, it is an easier matter, in practice, to properly apply the circumferentially spaced contacts 7 to the end 10 of the bulb, than it is to properly apply a continuous or annular contact, such as used in my said prior application.

The insulating centering collar 15, as shown, is frictionally secured to and rotated 15 with the holding collar of the lamp socket and it serves to hold the contact spring 18 out of contact with the surrounding portions of the lamp socket and alined with the contact 7. A short coiled spring 19 is compressed 20 between the insulating block 16 and the flanged rear end of the centering ring 15 and assists in holding the lamp holding collar 13 of the socket against unintentional rotation. The contact sleeve 8, the contact 25 plunger 17 and the contact spring 18 are connected, respectively, to lead wires 20, 22 and 21, of the three wire lamp circuit in which the lead 22 is common to both circuits.

What I claim is:

30 1. A two-filament electric light bulb provided on its shank with a surrounding contact sleeve and at the end of its shank with an axial contact and with circumferentially spaced electrically connected contacts, in

combination with a lamp socket having electrical contact with the surrounding sleeve of said light bulb, and provided with an axial contact engageable with the axial contact of said bulb, and having a contact spring surrounding said axial contact and provided with a front end portion engageable with the said circumferentially spaced contacts of said bulb. 35

2. A two-filament electric light bulb provided on its shank with a surrounding contact sleeve and at the end of its shank with an axial contact and with circumferentially spaced electrically connected contacts, in combination with a lamp socket having electrical contact with the surrounding sleeve 45 of said light bulb and provided with an axial contact engageable with the axial contact of said bulb, and having a contact spring surrounding said axial contact and provided with a front end portion engageable with the 50 said circumferentially spaced contacts of said bulb, the said front end of said contact spring, through an arc greater than the distance between the said circumferentially spaced contacts, with which it engages, being bent into a plane that is at a right angle to the axis of said socket. 55

In testimony whereof I affix my signature in presence of two witnesses.

OVERTON WINSTON.
